UNITED STATES PATENT OFFICE.

CLARA LUCILE MACKINNON, OF SEATTLE, WASHINGTON.

HAIRDRESSING DEVICE.

Application filed June 13, 1925. Serial No. 36,935.

This invention relates to improvements in hair dressing devices and more particularly to apparatus of that character especially designed for waving the hair; it being the principal object of the invention to provide a hair waving apparatus that can be applied or removed by the user, which does not require the application of heat and which is relatively inexpensive. More specifically stated, the object of the invention resides in the provision of a hair waving and curling device of the character above stated, comprising paired right and left side sets of waving devices adapted to be applied to the head of the user and to be attached to and held in place by an adjustable head band; each of said paired sets consisting of an under member and an outer member, the under members each having a plurality of ribs over which the hair may be combed and the outer members having co-operatively arranged ribs adapted to press the hair downwardly between the ribs of the under members so that after being held in this manner for some time the hair will retain the waves thus formed upon removal of the device therefrom.

It is a further object of the invention to provide curlers by means of which the hair that is not to be reached by the waving devices may be curled; the said curlers also being arranged for attachment to the head band.

Other objects of the invention reside in the various details of construction and combination of parts embodied in the invention and in the manner of assembling and using the same.

In accomplishing these and other objects of the invention, I have provided the improved details of construction, the preferred forms of which are illustrated in the accompanying drawings, wherein—

Fig. 1 is a perspective view of a hair dressing device embodied by the present invention as applied to the head of the user.

Fig. 2 is a perspective view of the head band with the left side set of waving devices shown in disconnected relation.

Fig. 3 is a sectional view taken through some of the waving ribs of one of the lower and upper waving devices, illustrating their relation when in use.

Fig. 4 is a perspective view of one of the ribs of an under member.

Fig. 5 is an edge view of one of the ribs of an upper member.

Fig. 6 is a perspective view of one of the detached curlers.

Fig. 7 is a sectional view of the same.

Referring more in detail to the several views of the drawings—

In a preferred form of construction the device comprises right and left side, paired waving devices that are adapted after being functionally applied to the hair, to be detachably fastened to and held in place by a head band 1 of a suitable material and which is equipped at its ends with means whereby they may be adjustably secured together; one form of attaching means consisting of a short stud 2 fixed in one end of the band and adapted to interlock with any one of a plurality of tapered slots 3 in the other end of the band.

Each pair, or set, of waving devices comprises an under member and a co-operating outer member; each of the under members consists of a spine 4 adapted to extend from front to back across the top of the head and to be detachably fixed at its ends to the head band 1; the ends of the spine being provided with slots 6 and the band having studs 8 fixed therein adapted to be received within the slots to retain the member in place. To this spine is attached a plurality of laterally extended ribs 5 that are shaped to conform to the shape of the head and which vary in length in accordance with their position, those at the front being somewhat shorter than those farther back. Each of these ribs is relatively thick in cross section and they are spaced substantially in parallel relation and are tapered toward their lower ends for detachable connection with the head band such as by being inserted beneath spring clips 7 pressed outwardly from the body of the band as is shown best in Figures 1 and 2.

In applying these devices to the head they are so positioned that the ends of the ribs will enter the hair along the top of the head much in the same manner as a comb would be applied. They are then pushed downwardly along the head so that the ends of the spine and the ends of the ribs may be attached to the headband to hold the device in place, and the hair is then combed back over or across the ribs.

After the under members have thus been inserted and attached, the outer members

are applied. Each outer member likewise consists of a spine 10 adapted to overlie the spine of the under member and to be attached also at its ends to the head band at 5 front and back of the head in the same manner as the spine of the under member. To the spine 10, laterally extending ribs 11 are fixed and adapted to be disposed over the hair and between each of the ribs of 10 the under member so as to press the hair downwardly between the ribs of the under member, as shown in Figure 3, so that after the device is removed, the hair will retain the waves thus formed.

15 It is preferred that the devices be made of celluloid, rubber, pyralin or any other suitable material that can be wound or formed about a steel wire frame. In cross section the ribs of the under members may assume 20 various forms, either semicircular, triangular or other desirable shapes in accordance with the character of wave desired.

The ribs of the upper members are differently constructed and consist of flattened 25 pieces of celluloid or rubber adapted to be fitted between the ribs of the under members in a manner as is shown in Figure 3 to effect the waving of the hair. These ribs 11 may be detachably fixed to the head band 30 in various ways, one way being to provide them at their ends with the common type of glove fastener 15 adapted to snap over button 16 on the band intermediate the spring clips which retain the ends of the ribs of the 35 under members.

To produce a better waving effect of the hair, it is preferred to provide the ribs of the under members along their upper edges with teeth 17 that are inclined toward the 40 top of the head in order to catch and retain the strands of hair drawn thereover and to likewise provide the ribs of the under members with serrations or teeth 18 that are inclined downwardly in a direction opposed 45 to the teeth of the under members so that they will catch the strands of hair and will pull them down between the ribs of the under members in such manner as to give it a more pronounced wave.

50 It is to be understood that while I have shown the device as applied in a certain manner, it is not intended that the parts be limited only to this particular manner of application as it is possible by shifting the head band, to apply the parts so that the waves will extend from front to back instead of across the head.

It is further apparent that such devices 55 may be made in various forms and applied 60 in various ways by variations in minor details of construction without departing from the spirit of the invention and for this reason I do not wish to limit the claims of the present device only to the form illustrated.

65 For the purpose of taking care of the

short hair that is not curled by the above described devices, I have provided the curlers as shown in Figure 6. Each of these comprises a clamp 20 made from a piece of 70 spring wire formed in a loop 21 having one end equipped with a round piece 22 about which the hair may be wound and the other end being equipped with a curved member 23 adapted to overlie and to be clamped against the piece 22 to retain the hair thereabout. Over these pieces is fitted a removable clamping plate 25. These curlers may be hooked onto the head band or left to hang free.

75 While it was not primarily the intention 80 to apply heat to the present device while in use, it is apparent that this could be done if desired by the placing of electrical heating elements within the ribs of the waving members and providing means whereby these 85 elements could be connected to a source of electricity.

Having thus described my invention, what I claim as new therein and desire to secure by Letters-Patent, is:

90 1. A hair dressing device comprising a head band and paired hair waving device adapted to be detachably fixed to said band and having co-operatively arranged ribs between which the hair may be held in 95 waves.

99 2. A hair dressing device comprising an adjustable head band, an under hair waving member comprising a spine adapted to be attached to the head band and a plurality 100 of ribs extended laterally from the spine across which the hair may be combed and adapted for attachment at their ends to the head band, and an outer member comprising a spine adapted to be attached to the 105 head band and ribs extended therefrom to overlie the hair and to lie between the ribs of the under member.

3. A device as set forth in claim 2 where- 110 in the ribs of the under and outer members are provided with oppositely inclined teeth.

4. In a hair dressing device of the character described, a head band, a spine detachably fixed at its ends to the head band to extend across the top of the head, ribs fixed 115 to the spine and adapted to have the hair drawn thereover, a second spine adapted for detachable connection to the head band to overlie the first spine and having ribs fixed thereto to overlie the hair between the ribs 120 of the first mentioned spine.

5. In a hair dressing device of the character described, a head band adapted to be 125 adjustably fitted to the head, a spine fas- 130 tened at its ends to the head band to extend across the top of the head, a plurality of ribs fixed to the spine in spaced apart relation over which the hair may be combed, a second spine detachably fixed at its ends to the head band to overlie the first spine and hav-

ing ribs extended therefrom to overlie the hair between the ribs; said ribs being detachably fixed at their ends to the head band.

6. In a hair dressing device, a head band provided at its ends with attaching means whereby it may be adjustably fitted about the head, a pair of spines fixed adjustably at their ends to the head band to extend across the top of the head from front to back, ribs fixed to the spines to extend in spaced relation along the sides of the head

so that the hair may be combed thereover, and attached at their ends to the head band, a second set of spines adjustably fixed to the head band to overlie the first set and having 15 ribs extended laterally to overlie the hair and to press it downwardly between the first mentioned ribs and means for attaching the ends of the latter ribs to the head band.

Signed at Seattle, King County, Wash- 20
ington, this 21st day of May, 1925.

CLARA LUCILE MacKINNON.
